(57) **CLAIM**

The ornamental design for a housing for communication devices or similar articles, substantially as shown.

DESCRIPTION

FIG. 1 is a perspective view of the ornamental housing for communications devices or similar articles.

FIG. 2 is a front-side plan view thereof.

FIG. 3 is a back-side plan view thereof.

FIG. 4 is a first side view thereof.

FIG. 5 is a second, opposite side view thereof.

FIG. 6 is an end view thereof; and,

FIG. 7 is an opposite end view thereof.

The broken line showings throughout the drawing views are for illustrative purposes only and form no part of the claimed design.
